JOHN M. YOUNG, OF SAN FRANCISCO, CALIFORNIA, ASSIGNOR TO AMERICAN CAN COMPANY, OF SAN FRANCISCO, CALIFORNIA, A CORPORATION OF NEW JERSEY.

APPARATUS FOR CUTTING AND DEPOSITING RING-LINERS ONTO THE FLANGE OF CAN-COVERS.

1,135,244.

Specification of Letters Patent. Patented Apr. 13, 1915.

Application filed October 31, 1912. Serial No. 728,929.

To all whom it may concern:

Be it known that I, JOHN M. YOUNG, a citizen of the United States, residing in the city and county of San Francisco and State of California, have invented certain new and useful Improvements in Apparatus for Cutting and Depositing Ring-Liners onto the Flanges of Can-Covers, of which the following is a specification.

10 The present invention relates to means for intermittently feeding a web of paper, cutting therefrom a ring liner, positioning a can cover with relation to the cutting mechanism, and forcing the ring liner onto the 15 flange of the can cover; the object of the invention being the production of a simple, efficient and durable machine for the cutting of ring liners, by the cutting or die punch of which not only serving to cut the ring 20 liners, but to place the cut liner onto the flange of the can cover, the die punch thus performing the double function of cutting the ring liner and forcing the same as one 25 operation onto the flange of the cover and by so doing enabling the carrier means for the covers and cut ring liners and the parts 30 associated therewith for placing the ring liner relative to the flange of the cover to be dispensed with.

35 To comprehend the invention reference should be had to the accompanying sheets of drawings, wherein—

Figure 1 is a vertical sectional view of the improved apparatus, taken in line —x—x— 35 Fig. 2 of the drawings, disclosing the position of the die punch, the means for actuating the same, the position of the web relative to the die punch and the can cover to receive the ring liner cut from the web, and the 40 means for feeding can covers into position beneath the die punch. Fig. 2 is a front elevation of the apparatus partly in section, the feed runway for the can covers being removed, said view illustrating the means 45 for actuating the feed control for the web from which the ring liner is stamped. Fig. 3 is a broken detail view of the web illustrating the cuts made therein by the die punchers.

50 In the drawings, the numeral 1 is used to designate any suitable form of a supporting frame for sustaining the working parts of the apparatus, which frame is provided

with an upwardly extended rearwardly inclined head block 2 carrying a bed plate 3. 55 Within the head block 2 is mounted for reciprocating movement a punch block 4, carrying the spaced die punches 5 and 6. The punch block 4 has reciprocating motion imparted thereto by means of a cam 6^a on the 60 drive shaft 7 engaging with the rolls 8 and 8' secured within the cross head 9 attached to the punch block 4 by the adjustable screw 9^a, the drive shaft working in bearing block 9' of the head block 2 of the frame 1, and 65 being driven preferably by means of a power belt working over a belt pulley 10 secured to one end of the drive shaft, the said shaft at its opposite end portion having attached thereto a cam grooved disk 10'. In the cam 70 groove 11 of said disk works a roll 12 secured to a stud 12' projecting from the upper end portion of a lever 13 fulcrumed to the head block 2, the lower end of said lever being pivotally connected to one end of a 75 slide rod 13' working in guides of the said head block 2 and being pivotally connected at its opposite end to a crank arm 14 upwardly projecting from a shaft 14' for actuating the hereinafter described mechanism 80 for imparting a step feed movement to the web 15 from which the ring liners are cut.

To the bed plate 3 is attached immediately over the punch opening 15' the die ring 16, with which coacts the punch 5 for cutting a 85 circular opening 16' in the web 15 of a diameter equal to the inner diameter of the ring liner to be cut therefrom, and said bed plate is also provided with a countersunk seat 17 for the reception of the can head or 90 cover 17' delivered therein through a slotted opening 18 from the feed chute or runway 18'. The seat 17 is in line with and immediately under the die punch 6, which is of a 95 diameter slightly larger than that of the punch 5 and on its downward movement cuts from the web 15 the ring liner 19 and forces the same within the seat 17 and onto the flange 17^a of the can cover 17' situated within the seat 17 to receive the same.

The web 15, cut to the desired width, is contained on a spool 19' mounted on a stud or spindle 20 situated at one side of the machine frame, and the said web is passed through the feed rollers 21, 22, and 23, 23', 105 the rollers 21 and 23' being held in frictional

contact with the said web 15 by the tension of the springs 24 acting against the bearing boxes 24' for said rollers slidably mounted in the guide brackets 25. On the shaft 25' for the roller 22 is secured a gear 26, in mesh with a gear 26', which said gear has an intermittent or step rotation imparted thereto for driving the roller 22 by means of the pawl 27 on the crank arm 14 which pawl is in locked engagement with the said gear 26' on each down stroke of the crank arm 14. This crank arm is thrown up and down through the action of the slide rod 13', which is reciprocated back and forth by the fulcrum lever 13 through the medium of its roll 12 working in the cam groove 11 of the disk 10'. The motion of the feed roller 22 is transmitted to the feed roller 23 by means of a sprocket chain 22' working on the sprocket wheels 23' on the shaft for the said rollers 22 and 23.

The can covers 17 are held within the chute or runway 18' by the stop pins 28 and 28' which are downward projections of the fulcrumed lever 29, and by the stop pin 29' depending from a bracket 30 secured to and forwardly projecting from the punch block 4, and which at its outer end carries a depending stud 30' for actuating or tripping the lever 29, the pin 28' of which is carried by the overweighted end thereof. The movement of these stop pins is such that covers 17' held thereby are released one at a time within the inclined chute or runway 18', the lowermost cover of the series when released by the upward movement of the stop pin 29' passing through the opening 18 into the seat 17 of the bed 3, being held therein by the stop pin 31 against passing outwardly through the discharge opening 32. This stop pin 31 is normally held upward by the spring held lock-bolt 32' acting against the block 33 through which the stop pin 31 is extended.

On the downward movement of the cross head 9 the punch head block 4 moving therewith, the stud 30' of the bracket 30 bears against the upper end of the fulcrumed lever 29, forcing downward the stop pin 28 and raising the stop pin 28', thus releasing a can cover 17' and allowing the same to move downwardly by gravity until engaged by the stop pin 29' placed within the runway 18' by the downward movement of the punch head block 4. On the upward stroke of the said punch head block the outer end of the lever 29 is released, and the stop pin 28' moves downwardly within the runway 18' to check the flow of the can cover, while the cover released by the upward movement of the stop pin 29' moves into the seat 17 through the opening 18 until arrested by the stop pin 31.

As the punches 5 and 6 are moved with the downward movement of the punch head

block, the punch 5 cuts a circular hole indicated by *a* from the web 15, while the die punch 6 of slightly increased diameter acts on the web where previously perforated by the punch 5 and cuts therefrom a ring liner 19, which cut or severed ring liner is forced downwardly by the die punch 6 into the seat 17 and onto the flange 17' of the can cover 17'. The die punch 6 thus cuts the ring liner from the web 15 and forces the same onto the flange of the cover 17' as a single operation, the web 15 remaining stationary over the bed plate 3 during the cutting action of the punches 5 and 6.

Owing to the space existing between the punches 5 and 6, the punch 5 is required to make one perforation of the web 15 before the same is presented to the action of the cutting die 6, so by the time one ring liner is cut from the web there will be three perforations in that portion of the web within the machine, those made by the punch 5 being represented by the letter *a* and the perforation of increased diameter made by the die punch 6 being represented by *b*—Fig. 3 of the drawings.

The stop pin 31 is lowered as the punch head block 4 approaches the limit of its downward movement by the shouldered portion 34 of a U-shaped spring 34' secured to and carried by the said punch head block moving into engagement with the projection 35 of the collar 33 and forcing the same down until the top of the pin 31 clears the outlet or discharge opening 32, in which position it remains until the die punch 6 moves out of the seat 17, so as to allow the can cover with its applied liner ring to slide by gravity out of said seat through the discharge opening 32, after which the shoulder 35' engages with the projection 35 and raises the stop pin 31. The spring held slide bolt 32' gives inwardly on the downward pressure exerted on the pin 31, but the moment the same is raised to place the collar 33 clear of the slide bolt, the same springs outwardly to hold the stop pin in locked position.

On the upstroke of the punch head block the lever 13 is operated to force outwardly the slide rod 13', which throwing downwardly the crank arm 14 carrying the pawl 27 in locked engagement with the gear 26' imparts a part rotation to said gear, which through the described interconnected parts operates the feed rollers 21—22 and 23—23', to advance the web 15 a given distance within the machine to place a perforation *a* thereof beneath the die punch 6 and an uncut surface beneath the die punch 5.

The mechanism for controlling the feeding of the web through the machine is thrown into action by the upward or return movement of the die plungers, the same remaining at rest on the downward stroke of the said plungers; the various working parts

of the apparatus being so timed relative to each other as to come into successive action at predetermined times.

I am aware that various changes may be made in the details of construction of the working parts of the apparatus herein shown and described without creating a departure from the spirit of the invention, the essential features of the invention residing 10 in the employment of reciprocating punch means for puncturing a web and severing from said punctured section thereof a ring liner for the flange of a can end cover and applying the said severed ring liner onto the 15 flange of the said cover, with means for feeding, positioning, and holding a can cover beneath the ring liner to be applied thereto, combined with devices thrown into action by the movement of the reciprocating 20 punch means for feeding the web in advance thereof.

Having thus described the invention what is claimed as new and desired to be protected by Letters Patent is—

25 1. An apparatus for cutting paper ring liners and applying the same to the flange of a can cover, the same comprising a reciprocating die punch, means for positioning a web of paper in advance of the die punch, 30 a can cover seat situated beneath the die punch for receiving can covers, devices for seating a can cover within said seat and beneath the web and in line with the punch, devices for retaining the can cover within 35 said seat against movement, mechanism for operating said punch to cut a ring liner from the web and place the same onto the flange of the held can cover, and means thrown into action by the movement of the 40 said punch for controlling the release of the held can cover.

2. An apparatus for cutting paper ring liners and applying the same to the flange of a can cover, the same comprising a vertically 45 movable reciprocating die punch, means for positioning a web of paper in advance of the die punch, a can cover seat situated beneath the said punch, locking devices for holding a can cover in said seat 50 against movement and beneath the web and in line with the die punch, and mechanism for actuating the said die punch to cut a ring liner from the web and apply the same to the flange of a can cover, and means 55 thrown into action by the movement of the said punch for actuating the lock devices for releasing the can cover with its applied liner to permit the discharge thereof from within its seat.

60 3. An apparatus for cutting and applying paper ring liners to the flange of can covers, the combination with a reciprocating die punch, of means for feeding a web of paper in advance of the die punch, a can cover 65 seat situated beneath said punch, lock-de-

vices for holding a can cover in said seat against movement and beneath the web and in line with the die punch, mechanism for actuating the die punch to cut a ring liner from the web and apply the same to the 70 flange of a held can cover and to return the die punch to normal position, and devices thrown into action during the movement of the die punch for actuating the feed means for the web for advancing the same through 75 the machine.

4. In an apparatus for the described purpose, the same comprising a plurality of vertically movable die punches of different diameters, devices for positioning a web in 80 advance of said punches, means for receiving and locking against movement a can cover beneath said web and in line with the punch of larger diameter, mechanism for actuating said punches to cause the 85 punch of smaller diameter to perforate the web and the punch of larger diameter to cut a ring liner from a perforated section of the web and applying the same onto the flange of the held can cover, and devices thrown into action by the movement of said punch for controlling the locking means for the can cover.

5. In an apparatus for the described purpose, the combination with a reciprocating 95 die punch for cutting a ring liner from a positioned web and applying the same as a single operation to the flange of a held can cover, means for receiving and locking a can cover against movement during such operation of the die punch, mechanism for imparting reciprocating movement to said punch, and devices operated by the movement of the punch for controlling the release of the held can cover.

6. In an apparatus for the described purpose, the combination with a die punch for cutting a ring liner from a positioned web, devices for receiving and holding a can cover against movement relative to said web 110 and in line with the die punch, mechanism for imparting reciprocating movement to said punch for cutting a ring liner from the web and applying the same to the flange of the held can cover on the cutting stroke 115 thereof as a single operation, and means thrown into action by the movement of the die plunger for releasing the holding devices for the lined can cover.

7. In an apparatus for the described purpose, the combination with a plurality of die punches of different diameters, of means for intermittently feeding a web in advance of said plungers, a feed chute for the can covers, of means for receiving and holding a 125 cover against movement beneath the web and in line with the die punch of larger diameter, mechanism for actuating said punches to cause the punch of smaller diameter to perforate the web and the punch of 130

larger diameter to cut from a perforated section of the web a ring liner and to apply the same to the flange of a held can cover as a continuation of its cutting stroke, and 5 devices thrown into action during the movement of the last mentioned punch for releasing the holding means for the lined can cover.

8. In an apparatus for the described purpose, the combination with a plurality of spaced vertically movable die punches of different diameters, of means for intermittently feeding a web in advance thereof, devices for positioning and holding a can cover 10 against movement beneath the web and in line with the die punch of larger diameter, mechanism for operating the said punches to cause the punch of smaller diameter to perforate the web and the punch of larger 15 diameter to cut from a perforated section thereof a ring liner and apply the same to the flange of the can cover, and means actuated by the movement of the last mentioned punch for releasing the holding devices for 20 the lined can cover.

9. In an apparatus for the described purpose, the combination with a plurality of spaced reciprocating die punches of different diameters, of means for intermittently feeding a web in advance thereof, devices 25 for positioning and holding a can cover against movement beneath the web and in line with the die punch of larger diameter, mechanism for operating the said punches 30 to cause the punch of smaller diameter to perforate the web and the punch of larger diameter to cut from a perforated section thereof a ring liner and apply the same to the flange of the can cover, and means 35 actuated by the movement of the last mentioned punch for releasing the holding devices for 40 the lined can cover.

can covers beneath the punch of larger diameter.

10. In a machine for the described purpose, the combination with a plurality of 45 reciprocating die punches of different diameters, of means for intermittently feeding a web in advance of said punches, devices for receiving a can cover and holding the same against movement beneath the web 50 and in line with the punch of larger diameter, mechanism for operating the die plungers for causing the plunger of smaller diameter to perforate the web and the plunger of larger diameter to cut a ring liner 55 from the perforated section of the web and apply the same to the flange of a can cover, and interconnected instrumentalities for actuating the feed means for the web, and controlling the feed of can covers to the 60 machine.

11. In a machine for the described purpose, the same comprising a reciprocating perforating punch and a reciprocating ring liner cutting punch, means for feeding a 65 web in advance of said punches, can cover retaining means, mechanism for actuating said punches to first perforate the web and then to cut a ring liner from the perforated section of the web and apply the same directly to the flange of the retained can cover, and devices actuated by the movement of the cutting punch for controlling the feed of the can covers thereto.

In testimony whereof I have signed my 75 name to this specification in the presence of two subscribing witnesses.

JOHN M. YOUNG.
